UNITED STATES PATENT OFFICE

2,512,161

FORMING DIE

Carl Ledel, Los Angeles, Calif., assignor of one-third to Peter Rice and one-third to Sam Schuster, both of Los Angeles, Calif.

Application February 18, 1946, Serial No. 648,379

4 Claims. (Cl. 153—21)

1

This invention relates to improvements in forming dies utilized in forming stampings or metal blanks into desired shapes by bending portions of the stampings or blanks relative to other portions thereof.

An object of the invention is to provide an improved forming die which can be easily and economically constructed and assembled and which will efficiently bend and shape a stamping or blank accurately and without scarring or otherwise detrimentally effecting the surface of the metal.

More specifically, an object of the invention is to provide an improved forming die wherein there are male and female die elements with the female die element equipped with a forming head adapted to telescope over the male die or punch and which is backed by a compressible material adapted to be squeezed laterally on engagement of the head with the base of the male die to squeeze or press the metal of the stamping or blank laterally into the desired position. All metals used in doing this class of work possess some inherent spring back and if, for example, a flat stamping is to have flanges or its side edges bent downwardly at right angles to the plane of the stamping it is necessary to undercut the sides of the punch or male die and to press the downwardly bent flange portions or side edge portions inwardly against these undercut sides of the punch so that on allowing for the spring back these portions after springing back will assume their desired positions exactly at right angles to the plane of the body of the stamping. By the improved die the compressible material that backs the head on the female die becomes squeezed and pressed laterally during the final closing movements of the die and provides a means for simply and automatically applying lateral pressure to the sides of the stamping to press them inwardly against the undercut sides of the punch or male die. This pressure is automatically released on opening the parts of the die.

Another object of the invention is to provide a forming die having the above-described characteristics wherein the head on the female die is so mounted as to be susceptible of some lateral movement as well as vertical movement that is required to compress the compressible material. By having the head thus floating with respect to the female die it may adjust itself with relation to the punch or male die. The amount of lateral movement need not be great as ordinarily only a movement of a few thousandths of an inch will ordinarily be required. Such movement, however, is quite important in work of this character, inasmuch as it enables the head to center itself with respect to the punch or male die and so adjusts itself that it will not gall or otherwise detrimentally effect the surface of the metal stamping.

2

With the foregoing and other objects in view, which will be made manifest in the following detailed description and specifically pointed out in the appended claims, reference is had to the accompanying drawings for an illustrative embodiment of the invention, wherein:

Fig. 1 is a view in side elevation of the improved forming die embodying the present invention;

Fig. 2 is a bottom plan view of the female part of the die or may be regarded as a horizontal section taken substantially upon the line 2—2 upon Fig. 1 in the direction indicated;

Fig. 3 is a top plan view of the male member of the die or may be regarded as a horizontal section taken substantially upon the line 3—3 upon Fig. 1 in the direction indicated;

Fig. 4 is a sectional view through the female die taken upon the line 4—4 upon Fig. 2 in the direction indicated;

Fig. 5 is a sectional view taken substantially upon the line 5—5 upon Fig. 3;

Fig. 6 is a partial view in vertical section taken substantially upon the line 6—6 upon Fig. 2 in the direction indicated;

Fig. 7 is a sectional view through the improved forming die illustrating it in its fully closed position;

Fig. 8 is a view in side elevation of the die illustrating the parts after the die has started to open and after a stamping has been formed; and

Fig. 9 is a perspective view of the completed formed stamping which is typical of the type of work that may be performed with the improved forming die.

Referring to the accompanying drawings wherein similar reference characters designate similar parts throughout, the improved die will be described in connection with the forming of an article from a stamping to produce an article

such as that illustrated in Fig. 9 although it will be appreciated by those skilled in the art that the die is in no way restricted to the formation of such articles and may be modified to form any type of article wherein portions of a stamping or blank of sheet metal are to be bent relatively to other portions.

The article illustrated in Fig. 9 as being typical is made from a sheet metal stamping or blank and when completely formed it is to have a top 10 in which there is an aperture 11 with one side 12 bent vertically downward and two ends 13 and 14 also bent vertically downward. The stamping or blank is initially cut or shaped to provide the top 10, the side 11, and two ends, 13 and 14 and

55 may have the aperture 11 stamped therein.

The improved die consists of a base 15 for the punch or male member. The punch or male member indicated at 16 has a boss 17 on its upper surface adapted to enter the hole 11 and a guide strip 18 against which the edge 19 of the stamping or blank is adapted to fit so as to positively

position the blank or stamping on the punch or male die. Other suitable means may be employed on the male die to positively locate the stamping thereon so that it will not have its position disturbed with respect thereto. In the forming of the article illustrated in Fig. 9 only three sides of the blank are to be bent downwardly with respect to the top 10 and consequently the edge 19 may be utilized to abut the guide strip 18. The three sides indicated by the side 12 and the ends 13 and 14 are to be at exactly right angles to the plane of the top 10. Virtually all metals utilized for this type of work possess some inherent spring back so that if the sides and ends were merely bent downwardly by the female die to a position at right angles to the top 10 on release of the die these portions would spring outwardly to some extent and would not retain their positions at right angles to the top 10. To make correction for this, one side and two ends of the punch or male die 16 are undercut as indicated at 20, the degree of undercut being dependent upon the amount of spring back that is inherently possessed by the metal of the stamping. Thus if the metal of the stamping has a great amount of inherent resiliency the undercut at 20 may have to be severe. On the other hand if the blank or stamping is not extremely springy the degree of undercut will be lessened to compensate therefor so that when the die is opened and the sides of the stamping spring back they will spring into a position at exactly right angles to the top 10. Manifestly if the sides of the stamping represented by the side 12 and the ends 13 and 14 are intended to be arranged at other than right angles to the top 10 the sides of the male die are so formed as to allow for the spring back and thus enable these sides to assume their intended positions with respect to the body of the stamping when the forming die is opened and spring back is allowed to occur. The punch or male member is secured to the base 15 in any suitable manner such as by bolts 21 and the base member may or may not be equipped with guide posts 22.

The female member of the die consists of a base 23 equipped with a shank 24 by which it may be attached to a press. The female die indicated at 25 is secured to the base 23 and has an indenture or recess generally indicated at 26 formed therein. The top portion of this recess indicated at 27 is shaped to accommodate a pressure pad or floater 28 to which a bolt 29 is secured that slidably extends through the top of the female die 25, the base 23, and the bottom of the shank 24. A compression spring 30 is disposed about this bolt and urges the pressure pad into its lowermost position. Guide studs 31 may be secured to the pressure pad and are receivable in apertures 32 in the top of the female die and in the bottom of the base 23. The bottom surface of the pressure pad may be shaped to partially receive the boss 17 and any guide pins such as those indicated at 33 on the guide strip 18. The pressure pad or floater is adapted to engage the stamping or blank S positioned on the male die and to press it downwardly thereon and to continue to apply pressure to the stamping as the female die descends. In plan it conforms generally to the plan of the male die.

The lower portion of the recess or indenture 26 is enlarged to accommodate a head 34 and a backing therefor indicated at 35. This backing is formed of a readily compressible material such as rubber neoprene or the like. The head 34 has an aperture therethrough indicated at 36 which

closely conforms to the shape of the punch or male die. Thus the internal dimensions of the aperture 36 are substantially equal to the external dimensions of the top of the punch 16 plus the thicknesses of the metal of the stamping S that is to be formed. Usually a very small amount of additional clearance is allowed this being in the neighborhood of one to three thousandths of an inch ordinarily. There is a small clearance indicated at 37 between the external edges of the head and the interior of the female die. Bolts 38 connect the head through the compressible material 35 to the female die 25. There are small clearances indicated at 39 between the bolts and the head 34 so that a small amount of lateral movement in any direction is permitted of the head 34 with respect to the female die. This lateral movement need not be great and frequently need not be more than one to three thousandths of an inch. The female die 25 and its base 23 have apertures therein to receive the guide posts 22 when these guide posts are employed.

The operation of the improved forming die is as follows: When the stamping or blank S has been positioned on top of the male die or punch 16 the female die is caused to descend and the pressure plate or floater 28 first engages the blank or stamping and presses it firmly against the punch. As the female die continues to descend the sides of the head 34 engage the projecting portions 12, 13 and 14 of the blank and bend these downwardly. Usually the bottom edges of the head 34 surrounding the aperture 36 are slightly rounded to facilitate this bending and to avoid shearing action. Finally as the female die descends, the head 34 passes entirely over the blank or stamping S and engages the base 15 of the male die assuming a position as illustrated in Fig. 7. In this position the head which initially protruded from the female die 25 is forced upwardly therein and highly compresses the compressible rubber like material 35 causing it to be squeezed laterally. Externally there is adequate clearance between the rubber like material 35 and the interior of the female die so that this material may be squeezed outwardly without danger of rupturing the female die. The rubber like material 35 is also squeezed inwardly as illustrated on Fig. 7 and thus applies considerable pressure to the downwardly bent sides of the stamping pressing them inwardly into firm engagement with the undercut sides 20 of the punch. When the female die is lifted the pressure on the rubber like material is released and this material returns to its normal position as illustrated in Figs. 4 and 5 and the head 34 is withdrawn over the stamping on the male die. As the material springs back from the undercut sides 20 it will spring into a position exactly at right angles to the top 10 or into the intended position with respect thereto.

It is to be observed that the small clearances 37 between the bolts 38 and the head 34 provides a small floating movement of the head with respect to the female die and with respect to the punch 16. Consequently even though there may be slight inaccuracies in fit between the guide posts 22 and the apertures in the female die or if the press is such that it will not uniformly cause the female die to descend vertically on the punch the head may self-center itself with respect to the punch and cause the sides 12, 13 and 14 to be bent downwardly without galling or scarring. Galling or scarring of the surfaces of the stamping may be avoided usually if but a very small amount of clearance is permissible and the

floating or self-centering action of the heat 34 even though very small will ordinarily adequately take care of any difficulties in this regard.

The bases 15 and 23 and the female die 25 may be formed of any strong inexpensive material. I find that Masonite is highly suitable for this purpose. Likewise the punch 20 and the head 34 may be formed of any strong homogeneous and inexpensive material that may be suitably employed for forming stampings.

It will be appreciated from the above described construction that forming dies of this character may be very easily and quickly constructed and assembled together. Frequently the same bases may be employed with a number of different punches or male dies and with a number of different female dies and their heads, it being merely necessary to substitute different dies on the bases.

Various changes may be made in the details of construction without departing from the spirit and scope of the invention as defined by the appended claims.

I claim:

1. A die apparatus comprising a male die or punch, a base to which the punch is fixedly secured, the base extending outwardly of the male die or punch, the male die or punch being undercut and adapted to have a piece of work positioned thereon, a female die including a body adapted to be moved toward the male die, the body having a recess, a pad of readily compressible material receivable in the recess and having its outer edges spaced from the walls of the recess to allow the pad to expand toward the walls, a head receivable in the recess and suspended from the body by bolts which slidably extend through the head and pad and which are fixedly secured to the body, the head being normally disposed at least partially out of the recess so as to contact the base prior to the body, the head and pad being apertured to fit around the male die when the female die is moved toward the male die, the head being adapted to contact the base after bending the work to compress the pad to permit the pad to bend the already bent portions of the work into the undercut portions of the male die.

2. A die apparatus comprising a male die or punch, a base to which the punch is fixedly secured, the base extending outwardly of the male die or punch, the male die or punch being undercut and adapted to have a piece of work positioned thereon, a female die including a body adapted to be moved toward the male die, the body having a recess, a pad of readily compressible material receivable in the recess and having its outer edges spaced from the walls of the recess to allow the pad to expand toward the walls, a head receivable in the recess and suspended from the body by bolts which slidably extend through the head and pad and which are fixedly secured to the body, the head being normally disposed at least partially out of the recess so as to contact the base prior to the body, there being clearance between the bolts and the head to allow limited lateral movement of the head to permit the head to center itself on the male die, the head being adapted to contact the base after bending the work to compress the pad to permit the pad to bend the already bent portions of the work into the undercut portions of the male die.

3. A die apparatus comprising a male die or punch, a base to which the punch is fixedly se-

cured, the base extending outwardly of the male die or punch, the male die or punch being undercut and adapted to have a piece of work positioned thereon, a female die including a body adapted to be moved toward the male die, means on the body contacting the work as the body is moved toward the male die to clamp the work on the male die, the body having a recess, a pad of readily compressible material receivable in the recess and having its outer edges spaced from the walls of the recess to allow the pad to expand toward the walls, a head receivable in the recess and suspended from the body by bolts which slidably extend through the head and pad and which are fixedly secured to the body, the head being normally disposed at least partially out of the recess so as to contact the base prior to the body, the head and pad being apertured to fit around the male die when the female die is moved toward the male die, the head being adapted to contact the base after bending the work to compress the pad to permit the pad to bend the already bent portions of the work into the undercut portions of the male die.

25 4. A die apparatus comprising a male die or punch, a base to which the punch is fixedly secured, the base extending outwardly of the male die or punch, the male die or punch being undercut and adapted to have a piece of work positioned thereon, a female die including a body adapted to be moved toward the male die, means on the body contacting the work as the body is moved toward the male die to clamp the work on the male die, the body having a recess, a pad of readily compressible material receivable in the recess and having its outer edges spaced from the walls of the recess to allow the pad to expand toward the walls, a head receivable in the recess and suspended from the body by bolts which slidably extend through the head and pad and which are fixedly secured to the body, the head being normally disposed at least partially out of the recess so as to contact the base prior to the body, there being clearance between the bolts and the head to allow limited lateral movement of the head to permit the head to center itself on the male die, the head being adapted to contact the base after bending the work to compress the pad to permit the pad to bend the already bent portions of the work into the undercut portions of the male die.
